UNITED STATES PATENT OFFICE.

LEWIS S. WATRES, OF SCRANTON, PENNSYLVANIA, ASSIGNOR OF FORTY ONE-HUNDREDTHS TO CLARENCE D. SIMPSON AND TWENTY ONE-HUNDREDTHS TO HENRY H. BRADY, BOTH OF SCRANTON, PENNSYLVANIA.

MEANS FOR DETERMINING THE WEIGHT OF FUEL CARRIED BY A LOCOMOTIVE-TENDER.

1,136,633.

Specification of Letters Patent.

Patented Apr. 20, 1915.

Application filed May 16, 1913. Serial No. 767,997.

To all whom it may concern:

Be it known that I, LEWIS S. WATRES, a citizen of the United States of America, residing in Scranton, county of Lackawanna, 5 and State of Pennsylvania, have invented a certain new and useful Improved Means for Determining the Weight of Fuel Carried by a Locomotive-Tender, of which the following is a specification.

10 The object of this invention is to provide a means whereby the weight of fuel carried by a tender may be determined, for instance, at the beginning, of a run and again at the conclusion thereof.

15 The embodiment of the invention hereafter described and illustrated in the drawings is, by means of a special fuel container located in the tender, free to move vertically therein, and the actuating parts of a weight 20 indicating closed liquid system placed between the tender and fuel container, whereby the fuel container is supported.

In the accompanying drawings: Figure 1 is a longitudinal vertical section through the 25 body of a locomotive tender omitting the running gear and showing a means of indicating the weight of the fuel and a special container therefor: Fig. 2, a front elevation thereof partly broken away: Fig. 3, a 30 detailed cross section showing a diaphragm for supporting the fuel container: Fig. 4, a side elevation partly in section showing the sills of the body of the tender and their means of support on the truck bolsters: 35 Fig. 5, a plan view of one such truck: and Fig. 6, a sectional detail view, somewhat diagrammatic, illustrating the operation of the weight indicating devices.

In Fig. 1, the interior of the body of the 40 tender is divided to form a water tank 1, which, in this instance, is shown as extending to the top of the tender body at the rear and from thence downwardly and forwardly at an angle as at 2; and then horizontally as at 3. A horizontal step or shoulder 4 is formed in the inclined wall 2 adjacent its upper part. Within the chamber thus formed is a coal container 5 which has vertical sides fitting within the side walls of 45 the tender and a horizontal floor 6 and upwardly inclined wall 7 conforming generally to the slope of the parts 2, 3, of the wall of the water tank. 8 indicates the ordinary doors forming a closure at the front end of

the coal container. The container with fuel 55 therein is carried upon a system of weighing devices, a preferred form of which is shown in Figs. 1 and 3. This system is one in which the container is carried upon diaphragms of which there may be three; one 60 at the top located midway between the side walls of the body, and two at the bottom located at the respective front corners of the container. The construction of each is shown in the sectional view Fig. 3. To the 65 under side or floor 6, or 7, there is secured a short post 9 securely united at its lower end to the center of a corrugated diaphragm 10 opposite which, being with a suitable space 70 between them, is a similar corrugated diaphragm 11. These circular diaphragms are spaced apart by a ring 12 adjacent their peripheries through which pass any suitable number of securing bolts 13. Integrally united with or secured to the bottom of the 75 lower diaphragm 11 is a circular plate or hub 14 from which extends centrally a screw bolt 15 that passes through an aperture in the wall 3, or 2, of the water tank and is secured by a nut 16. The space between the 80 diaphragms 10, 11, of the upper central supporting diaphragm system 17 is connected by a pipe 18 with space between the diaphragms of one of the lower diaphragm supporting systems 19, which latter space is connected by pipe 20 with the space between the diaphragms of the other lower diaphragm supporting system; and from the space between the diaphragms of one of the lower supporting systems, (the drawing indicating the system 19) there extends a pipe 21 to the lower side of a gage or indicating diaphragm which divides horizontally a suitable casing 20^a from the upper side of which extends a gage tube 21^a supported vertically 85 against a plate 22 secured to the side of the tender and inscribed with a scale 23. The closed system comprising pipe 21, 20 and 18 and the spaces between the pairs of diaphragms of the three diaphragm supporting 90 systems is completely filled with a liquid, preferably non-freezing. The liquid may be mercury, alcohol, kerosene, etc. The diaphragms are annularly corrugated and susceptible of elastic vibration and they are best 95 made of steel of appropriate thickness and of such diameter as is desirable considering the load that they are to carry. In the 100

space above the diaphragm in the gage case 20^a is placed a suitable liquid which will rise in the tube 21^a upon contraction of the chamber above the diaphragm due to pressure exerted under said diaphragm by the load on the diaphragms of the supporting devices. This liquid will, of course, be non-volatile if the upper end of tube 21^a be open to the atmosphere. The scale of the indicating tube may be calibrated to conform to the conditions of its special container and be made to indicate the weight of fuel only. When the container is full the diaphragm yield transferring pressure to the non compressible liquid medium by which it is transferred to the indicating gage diaphragm thereby forcing any suitable liquid above it up into the gage-tube from which a reading may be taken. As the quantity of fuel decreases, the pressure upon the supporting diaphragm system is reduced.

The modification of Figs. 4, 5 and 6, which forms the subject of another application for Letters Patent filed by me November 7, 1913, Ser. No. 799,755, consists in dividing the king bolts of the trucks and interposing diaphragms, the spaces between which are filled with liquid and connected up in the general manner above described. The body bolsters 24 have the usual seats 25 for the king bolts as also have the truck bolsters 26. The king bolt is composed of upper and lower sections 28, 29 each respectively integrally, or otherwise suitably connected with, corrugated diaphragms 30, 31. The general scheme is plainly disclosed in Figs. 4 and 6. In the latter figure there is the before described arrangement of the recording diaphragm constituting the end of the compressed liquid system. 21^a is the gage tube which is connected with an upper wall of the gage diaphragm by a flexible or elastic connection or tubing 32.

Fig. 5 shows the plan of an ordinary truck. Since the truck swings with reference to the car body, the pipe 32^a (Fig. 4) leading from the rear king bolt diaphragm suspension comprises a hinge section 33 from whence the pipe is continued to the diaphragm suspension of the forward truck and thence by hinge connection 34 to the gage scale. In this latter modification, the gage may be calibrated so as to indicate only the fuel weights, or it may indicate total weights.

While I have shown both diaphragms of each pair corrugated and deem that arrangement to be most efficient, it is not in fact

necessary. The corrugations are employed to increase the capacity of the diaphragm for compression and reaction. In both modifications shown, the load is carried by the liquid under pressure.

While the system of support shown in the drawing is hydraulic, the invention broadly considered is deemed to comprise other means of support or suspension by which the described results may be obtained.

I claim:

1. The combination with a locomotive tender body of a fuel container located therein as an independent lining thereto and adapted to move vertically relative to the tender body, yielding liquid containers comprising diaphragm heads connected to the fuel container and tender body a gage attached to the tender body and a pipe connecting the gage with the liquid containers whereby vertical relation of the fuel container to the tender body will cause the weight of fuel to be indicated on the gage.

2. A locomotive tender comprising a water tank, a coal container, a closed liquid system comprising a diaphragm supporting means carrying the weight of the container and its contents, and a gage forming part of said closed system whereby variations of pressure imposed upon the confined liquid by variations of amount of fuel in said container may be made to operate an indicating gage.

3. A locomotive tender comprising a water tank, a coal container, a closed liquid system comprising a diaphragm supporting means carrying the weight of the container and its contents, and a gage consisting of a casing divided by a diaphragm one chamber of which is connected to the diaphragm supports forming part of said closed system and the other chamber provided with a tube and filled with a liquid, whereby variation of pressure imposed on the liquid in the closed system will actuate the gage diaphragm causing variations of amount of fuel in said container to be indicated in said gage tube whereby variations of pressure imposed upon the confined liquid by variations of amount of fuel in said container may be made to operate an indicating gage.

In testimony whereof, I have hereunto subscribed my name.

LEWIS S. WATRES.
